UNITED STATES PATENT OFFICE.

SAMUEL RACKMALES, OF BALTIMORE, MARYLAND.

SALIVA COLLECTOR FOR SMOKING EQUIPMENT.

Application filed March 14, 1927. Serial No. 175,315.

The invention aims to provide an extremely simple and inexpensive, yet an efficient and desirable device for use in smoking equipment, such as a pipe, a cigar holder or a cigarette holder, for the purpose of collecting saliva which would otherwise run to the tobacco, with the well known disadvantages.

With the foregoing in view, the invention resides in the novel subject matter herein-after described and claimed, the description being supplemented by the accompanying drawing.

Fig. 1 is a side elevation partly in section showing one form of construction.

Fig. 2 is a bottom plan view of a portion of the construction shown in Fig. 1.

Fig. 3 is a central longitudinal sectional view through a portion of the stem and the saliva collector therein.

Fig. 4 is a transverse sectional view on line 4—4 of Fig. 3.

Fig. 5 is a side elevation partly in section showing a different form of construction.

Fig. 6 is a fragmentary side elevation partly in section, showing a still further form of construction.

In the drawing above briefly described, the numeral 7 designates a tube open from end to end and adapted for central disposition in a passage 8 of smoking equipment, for instance, a pipe or a holder for a cigar or cigarette. At spaced points, the tube 7 is formed with annular outstanding flanges 9 which are adapted to engage the inner side of the passage 8, coacting therewith in forming pockets 10 to receive saliva. At suitable points, the lower side of the tube 7 is formed with openings 11, to conduct all saliva running down the tube 7 into the pockets 10, thus preventing such saliva from reaching the tobacco.

The tube 7 may be integral with a mouth-

piece 12, as in Figs. 1, 2 and 3, may fit with- 45 in the mouth-piece as indicated at 12^a in Fig. 5, or may have a socket 7^a formed on its outer end, to receive the front end of a mouth-piece 12^b, as disclosed in Fig. 6. Moreover, the saliva collecting device may be either 50 straight or curved, according to the design of the pipe or the like with which it is to be used.

Regardless of such variations as those depicted in the three forms of the invention herein disclosed, the device will be highly efficient to collect the saliva and to effectively clean out the passage 8 when outwardly pulled therefrom. Attention is also invited to the fact that the device permits free, un- 55 interrupted passage of the smoke from the fire to the mouth, instead of necessitating a tortuous course such as a number of some- 60 what analogous devices heretofore produced.

If desired, the lower side of the tube 7 65 may be cut away somewhat at the openings 11, as shown at 11^a in Figs. 1 to 4, thus somewhat increasing the size of the saliva pockets 10 and permitting the saliva to more readily run into said pockets when they be- 70 come almost filled.

I claim:

In smoking equipment, a saliva collector for disposition in a passage, said collector comprising a tube open from end to end to 75 conduct the smoke uninterruptedly, and annular flanges projecting outwardly from said tube at longitudinally spaced points, said flanges being adapted to engage the pas- 80 sage wall to coact therewith in forming saliva collecting pockets, the lower side of said tube having openings to permit all saliva running down the interior of the tube to enter said pockets.

In testimony whereof I have hereunto af- 85 fixed my signature.

SAMUEL RACKMALES.
